UNITED STATES PATENT OFFICE.

VICTOR H. JENNINGS, OF WORCESTER, MASSACHUSETTS, ASSIGNOR TO UNIVERSAL PATENTS COMPANY, OF WOONSOCKET, RHODE ISLAND, A CORPORATION OF RHODE ISLAND.

WOVEN CARRIER.

1,275,436.

Specification of Letters Patent. Patented Aug. 13, 1918.

Application filed May 7, 1917. Serial No. 167,092.

To all whom it may concern:

Be it known that I, VICTOR H. JENNINGS, a citizen of the United States, residing at Worcester, in the county of Worcester, 5 State of Massachusetts, have invented a certain new and useful Improvement in Woven Carriers, of which the following is a specification, reference being had therein to the accompanying drawings.

10. The invention has relation to woven carriers of the class having pockets with closed bottoms and in which the pockets are divided above said bottoms into compartments, one in front of another, by transverse vertical partitions. It is applicable especially in the case of carriers on the order of those employed as cartridge-carriers, but is not restricted necessarily to cartridge-carriers.
15. The invention provides a pocketed carrier which may comprise either a single pocket of novel constructional features, or a series of such pockets.

General objects of the invention are, by 25 improvements in the constructional features of partitioned closed-bottom carrier-pockets, to enable carriers having such pockets to be produced by simplified weaving operations and appliances, facilitate and expedite their production, and lessen the cost of manufacturing. Heretofore, carriers of this class have been produced by complicated operations and procedure in weaving, and by the employment of special loom 30 mechanism employing extensive and elaborate pattern mechanism. The cost of production has been considerable. Another object is to provide for the production of a partitioned pocket having a front which is 35 smooth and free from gathers or wrinkles in the lower part thereof. Heretofore, in order to secure the required reduction in the size of the lower portions of pockets having upper portions of the required fullness and 40 internal capacity, it has been customary to gather the said lower portions in the course of the weaving.

The invention consists in a carrier furnished with a woven pocket having its bottom closed in the weaving, and also having one or more flat transverse partitions of double or two-ply thickness dividing the pocket into front and rear compartments above the closed bottom, with such partition 45 or partitions formed of intermediate por-

tions of the pocket side-walls, which respectively are doubled inwardly upon themselves in vertically-extending folds having the two sides of each thereof secured together flatwise, and with the inner portions 60 of the two opposite folds secured together.

The drawings illustrate a woven carrier embodying the invention.

Figure 1 of the drawings is a front view of a single pocket, with a portion of its 65 front broken away.

Fig. 2 is a top view of the said pocket.

Fig. 3 is a front view of the woven pocket blank before being finished.

Fig. 4 is a view looking at the lower edge 70 of the said blank.

Fig. 5 is a top view of the said blank, representing the latter as having the middle portions of its side-walls brought together and fastened together, as in forming a partition. 75

Fig. 6 is a side view of the blank in the condition in which it is represented in Fig. 5.

The illustrated embodiment of the invention is formed with a single partition. A carrier having two partitions, or even more, may be produced, as will be apparent, by an extension of the same principles that are utilized in producing the single partition 80 85 that is herein shown.

In the drawings, 1 designates a portion of the body-web or band of a carrier, such portion being located at one side, laterally, of the pocket which is about to be described. 90 2, Figs. 2 and 5, is the pocket-back, it being a continuation of the said body-web or band. 3 is the pocket-front, it being integrally joined in the weaving to the pocket-back at the bottom of the pocket, as shown best in 95 Figs. 4 and 6. 4, in Fig. 2, is a partition intermediate the pocket-back and pocket-front, dividing the pocket above its closed bottom 5 into front and rear compartments 6 and 7. At 8 is a portion of the body-web 100 or band which is located at the other side, laterally, of the pocket. In practice, the pocket usually will be supplied with a cover-flap of approved character, and with fastening-devices for such cover-flap designed to 105 secure the latter in place when closed down over the pocket. These features have been omitted from the drawings, as not included in the invention.

The formation of the partition 4 is shown 110

best in Fig. 2, which illustrates its double or two-ply thickness, and the manner in which intermediate portions of the pocket side-walls are doubled or folded inwardly 5 upon themselves in vertically-extending folds (see also Fig. 1) having the two sides of each thereof close against each other flatwise. Figs. 5 and 6 show how the inner portions of the bends or folds are secured to 10 each other by a vertical line of stitches 9, and Fig. 1 shows at 10 some of the stitches by which the two sides of the respective folds are secured together flatwise after the folds have been connected together as in 15 Figs. 5 and 6. A line of stitches 10 extending across the top of the partition throughout substantially the width of the pocket, so as to bind the double or two-ply thickness of the partition together as in Fig. 20 2, is sufficient to secure the two sides together flatwise. When it is desired to produce a pocket which tapers transversely toward its bottom as in Fig. 1, the bends or 25 folds may be secured together so as to overlap with each other in a line that is somewhat inclined or oblique transversely.

To permit of the infolding of the pocket side-walls it is necessary that in the case of the pocket as produced in a loom the 30 side-walls should be of unusual relative dimensions in the direction from the pocket-back to the pocket-front. The production of a pocket with side-walls of such relative dimensions would be difficult or impossible 35 if the construction of the pocket, as woven, and the procedure in weaving, should be the same as heretofore in the case of pockets not woven with partitions. Accordingly, and preferably, the pocket or pocket-blank 40 is woven as illustrated in Figs. 3 and 4, namely with side-wall web-portions 14, 15, which are free at their lower edges. The said side-wall web-portions are produced as plain web-strips of the required proportions 45 to permit the infolding, and at the same time produce compartments of the required dimensions from back to front.

In weaving the pocket-web or pocket-blank shown in Figs. 3 and 4, the portion 50 1 of the body-web or band first is woven of the required thickness. On arriving at the point at which side-wall web-portion 14 should spring from the said body-web or band, certain of the warp-threads embodied 55 in the said portion 1 of the body-web or band are left idle while the remainder of such warp threads are interwoven with weft-thread or filling to form a separate ply having upper and lower selvages. The 60 weaving of this separate ply is continued until a side-wall web-portion 14 of dimensions which will permit the infolding, and afford the desired internal capacity of the compartments 6 and 7, has been produced. 65 A continuation of the separate ply forming

the side-wall web-portion 14 forms also the pocket-front 3, but the pocket-front 3 and the pocket-back 2 are woven concurrently by causing the weft-thread or filling to pass first from the edge of the web at which 70 the open mouth of the pocket is located, through the warp-threads of the said separate ply, then back to the starting edge of the web through the warp-threads which were left idle during the weaving of side-wall web-portion 14, and then reversely 75 through the latter warp-threads and back through those of the separate ply to the starting edge again, and so on as before. This mode of weaving produces a pocket-front and a pocket-back which are united 80 integrally at the bottom of the pocket in the weaving, by means of the weft-thread or filling passing from the ply constituting the pocket-front to the ply constituting the 85 pocket-back, and vice versa, and as usual, also, it provides the pocket-front and pocket-back, respectively, with selvages at the open mouth of the pocket. The weaving 90 of the pocket-front and pocket-back concurrently is continued until they have been produced of the required dimensions for a pocket of the desired width from side to side. Preferably they will be equal, although to a certain extent a greater number 95 of picks of weft-thread or filling may be incorporated in well-known manner in the pocket-front than in the pocket-back. Then the weaving of the pocket-back is discontinued, while the weaving of the separate 100 ply is continued to form the side-wall web-portion 15 with upper and lower selvages. When the said side-wall web-portion 15 has been produced of the required dimensions, the said separate ply, and that constituting 105 the pocket-back are bound together in the weaving, and the weaving of the portion 8 of the body-web or band is proceeded with. The next succeeding pocket, of the carrier-web as woven in a loom, is produced by a 110 repetition of the described procedure. The carrier-web formed with a succession of pockets will, as usual, be divided up into lengths comprising one or more pockets, as 115 desired.

What is claimed as the invention is:—

1. A carrier furnished with a woven pocket having its bottom closed in the weaving, and also having a flat transverse partition of double or two-ply thickness dividing the pocket into front and rear compartments above the closed bottom, with such partition formed of intermediate portions of the pocket side-walls, which respectively are doubled inwardly upon 120 themselves in vertically-extending folds having the two sides of each thereof secured together flatwise, and with the inner portions of the two opposite folds secured 125 together. 130

2. A carrier furnished with a woven pocket having its bottom closed in the weaving, and also having a flat transverse partition of double or two-ply thickness dividing the pocket into front and rear compartments above the closed bottom, with such partition formed of intermediate portions of the pocket side-walls having selvaged lower edges, which respectively are doubled inwardly upon themselves in ver-

tically-extending folds having the two sides of each thereof secured together flatwise, and with the inner portions of the two opposite folds secured together.

In testimony whereof I affix my signature ¹⁵ in presence of two witnesses.

VICTOR H. JENNINGS.
